UNITED STATES PATENT OFFICE.

JAMES R. WILLIAMS, OF BLAIR STATION, PENNSYLVANIA.

LIFE-SAVING BELT.

1,368,529.

Specification of Letters Patent. Patented Feb. 15, 1921.

Application filed April 9, 1920. Serial No. 372,583.

To all whom it may concern:

Be it known that I, JAMES R. WILLIAMS, a citizen of Jamaica, British West Indies, residing at Blair Station, in the county of 5 Allegheny and State of Pennsylvania, have invented certain new and useful Improvements in Life-Saving Belts, of which the following is a specification.

This invention relates to life belts and 10 particularly to combination life belts and life suits.

The primary object is to provide a device which may be worn on a life suit such as is employed for saving lives from catastrophes on the sea.

One of the objects of the invention is to provide a life saving suit upon which may be mounted or attached a life belt which serves to cause the body to float and also 20 provides compartments in which may be stored food and water.

In catastrophes at sea it often happens that persons wearing life belts and life saving suits will suffer greater hardships from 25 lack of nourishment than is experienced by their exposure to the water and action of the elements.

The invention therefore contemplates the provision for supplying the unfortunate 30 person with a supply of food and fresh water, which may be consumed while being buoyed up by the life belt.

Other objects of the invention will appear from a consideration of the following 35 description and accompanying drawings, wherein:—

Figure 1 is a view of the apparatus illustrating its manner of use.

Fig. 2 is a perspective view of a portion 40 of the trunks constituting the life saving suit and illustrating the manner of holding the life belt in position.

Fig. 3 is a perspective view of one of the attaching or retaining brackets for the life 45 belt.

Fig. 4 is a perspective view of the life belt, and

Fig. 5 is a transverse section through one of the food containers.

The life saving suit comprises the body 50 enveloping garment of water proof material designed to fit the body of the person in a manner that will permit free movement of the limbs. A helmet is also included in the suit and fits snugly over the head of the person and is laced or other-

wise fastened as shown in Fig. 1 to completely exclude the water and permit only the features to be exposed.

Around the waist portion of the trunks 60 of the suit is a series of brackets 5 which are held in position by suitable fastening means, each of which consists of a fastening plate 6 provided with laterally projecting flanges 7 which are arranged in super- 65 posed relation when the brackets are in position on the suit.

The life belt shown in Fig. 4 consists of the band 8 which may or not be of elastic material but which is of the same width 70 as the width of the space between the flanges 7 of each bracket. Attached to the belt at regular intervals throughout the length thereof is a series of buoyant elements 9. The belt has separated ends so that it may 75 be conveniently donned or removed. At each end of the belt is a container, the food container being indicated at 10 and the liquid container being indicated at 11. A cross section of the food container is 80 shown in Fig. 5 and it is designed to contain a quantity of food and is provided with a removable cover 12 arranged to form a water tight connection with the container so that water will be excluded from the 85 same. The liquid container 11 is constructed in substantially the same manner and is designed to contain a quantity of fresh water or other liquid which may be consumed by the person using the apparatus. 90 A tube 13 of any desired length leads into the liquid container 11.

Attached to the container 11 is a strap 14 fixed by fastening members 15 and which carries a buckle 16 at its free end. The 95 other container 10 has a strap 17 attached thereto by the fastening members 18 and this strap is perforated with a series of openings in the manner commonly used for engaging the ends of straps with a buckle 100 so that in this instance the two straps may be drawn together and fastened whereby the belt will be firmly held about the waist of the wearer with the two containers 10 and 11 directly in front of the wearer and with- 105 in convenient reach.

The series of brackets 5 extending around the life saving suit support the life belt in position and prevent it from being moved up too high on the body so that the person 110 using the suit will not be likely to be turned from an upright position.

Minor changes may be made in the details of construction without departing from the spirit of the invention or the scope of the appended claims.

5. What is claimed is:—

1. The combination with a life saving suit; of a series of brackets secured around the waist thereof, a removable belt including a band of a width to fit the said brackets and having a series of buoyant members secured to the band, the said brackets including outstanding flanges adapted to overlie the upper and lower portions of the said buoyant members whereby the said belt will be maintained in position at the waist of the life saving suit.
2. The combination with a life saving suit having its waist portion provided with a plurality of brackets in the form of attaching members provided with outstanding flanges, the flanges on each bracket being in superposed relation, of a life belt including a band of a width equal to the width of the space between the said outstanding flanges in the brackets, a series of buoyant members attached to the band and also adapted to be engaged by the said flanges on the bracket members, and means to fasten the ends of the life belt together.
3. The combination with a life saving suit having bracket members provided with outstanding flanges, of a life belt including

a band having a series of buoyant members attached thereto and provided at each end with a container, the said buoyant members and containers being adapted to be fitted between the said outstanding flanges on the said bracket members whereby the life belt will be retained in position against displacement.

4. The combination with a life saving suit provided with a series of bracket members having outstanding flanges arranged in superposed relation, of a life belt including a band equipped with a series of buoyant members longitudinally spaced apart on the band, each end of the band being provided with a container, a strap member secured to each container and adapted to be fastened together whereby the belt may be secured at its separated ends, the said superposed flanges on the brackets engaging the upper and lower portions of the edges of the band and the tops and bottoms of the said buoyant members and containers whereby the said life belt is held in position on the waist portion of the said life saving suit.

In testimony whereof, I have affixed my signature in the presence of two witnesses.

JAMES R. WILLIAMS.
